UNITED STATES PATENT OFFICE.

MARO S. CHAPMAN, OF MANCHESTER, CONNECTICUT.

ENVELOPE.

SPECIFICATION forming part of Letters Patent No. 470,743, dated March 15, 1892.

Application filed October 17, 1889. Serial No. 327,377. (No model.)

To all whom it may concern:

Be it known that I, MARO S. CHAPMAN, of Manchester, in the county of Hartford and State of Connecticut, have invented a certain new and useful Improvement in Envelopes, of which the following is a full, clear, and exact description, whereby any one skilled in the art can make and use the same.

The object of the invention is to provide an envelope that shall have means for effectually sealing it against opening without so destroying or altering the parts as to prevent any resealing without leaving clear proof of the fact that the envelope has been tampered with.

To this end my invention consists in an envelope having a peculiar sealing device, as more particularly hereinafter described, and pointed out in the claims.

Referring to the drawings, Figure 1 is a detail view of one form of envelope embodying my invention, shown with the flap open. Fig. 2 is a plan view of same closed. Fig. 3 is a detail view, on enlarged scale, in section through the gum seal and the edge of the envelope. Fig. 4 is a detail view of a modified form of my invention, shown with flap open on one side. Fig. 5 is a detail view in section, on enlarged scale, through the edge of the envelope. Fig. 6 is a detail view of another modified form, shown with flap open on one side. Fig. 7 is a detail view of another modified form, shown with flap open. Fig. 8 is a detail view in section through the sealing-edge, on enlarged scale, in position before sealing. Fig. 9 is a detail sectional view, on enlarged scale, of the envelope sealed.

In the accompanying drawings the letter *a* denotes the envelope or package, made, preferably, of paper and closed on three sides by folding over the flaps or edges, the end flaps *a''* being folded in first, sealed together at *a³*, and the bottom *a'* then folded over and sealed to the end flaps at the seams *a⁴*, the edges of the bottom flap at this point being preferably serrated or roughened, so as to provide an additional safeguard against opening. When the envelope-blank is opened out, a broad band of gum, glue, or like adhesive material is smeared along the lines where the folds are to go, so that when the envelope is folded there is a gum seal *b* extending completely about three sides of the envelope, extending from

the outer edge to a certain distance inward, the inner line of this gum seal being denoted by the dotted line *b'*. The upper edge of the envelope is cut away at *c*, so that when the top flap *d* is folded over the gummed surfaces *d'* are brought together and may be sealed, so that a gum seal is caused to extend across the top of the envelope as well as about the bottom and sides. The back of the envelope, along the upper surface, is provided with a sealing layer, the gum portions being indicated in the drawings by the surface shading in fine lines.

In addition to the top flap *d* the infolded bottom flap is provided with supplemental flaps *e*, the under surfaces of which are gummed, so as to fold down upon the top flap after the latter has been sealed for the purpose of affording an additional safeguard. The supplemental flaps *e* are provided with an embossed device *e'* or with a figure or mark made in a sympathetic ink that will either evaporate or flow readily under moisture and heat, so that if any attempt is made to unseal the envelope the sharpness of the embossed figure will be destroyed or the condition of the ink will disclose the fact.

The edges of the envelope on at least three sides may be provided with embossed lines *f* by a suitable press or embossing tool, the substance of the paper being indented in sharply-defined lines, so that it is practically impossible to separate this gummed and embossed edge without tearing or cutting through the substance of the paper. This feature of my invention is illustrated in the form of envelope shown in Figs. 3 to 8 of the drawings. In these figures the envelope is of slightly-different form so far as the several end and bottom folds are concerned; but they all embody the main features of my invention that resides in the use of the solid gum seal all around the envelope, and they have the further security against opening by steaming of the edge of the embossing. The top flaps, that are the last ones to be sealed, are preferably so made as to have the opposite and contact-faces of the flaps provided with layers of gum, so that the gummed surfaces may be brought together and sealed, a more thorough union of the parts being possible when each is provided with a layer of gum.

One feature of my improvement consists in making the top flap of the envelope with one or more deep indentations along the edge, as shown in Fig. 4, the edge of this indented portion being nearer the top edge of the envelope than is the inner edge of the gum seal. The object of this is to prevent any lifting of the edge of the flap and making a cut through the seal, which cut may afterward be concealed by refolding and sealing the top flap.

I claim as my invention—

1. As an improved article of manufacture, an envelope provided at its edge with a solid gum seal and an embossed line or lines along such seal, the upper flap having its under surface covered with an adhesive material and adapted to be sealed over a portion of the lower flap, and the lower flap having portions adapted to be sealed over the upper flap, all substantially as described.

2. As an improved article of manufacture, an envelope provided about its edge with a solid gum seal and an embossed line or lines along such seal, the upper flap provided with one or more deep indentations and having its under surface covered with an adhesive material and adapted to be sealed over a portion of the lower flap, and the lower flap having

portions adapted to be sealed over the upper flap, all substantially as described.

3. As an improved article of manufacture, an envelope provided about its edge with a solid gum seal and an embossed line or lines along such seal, the upper flap having its under surface covered with an adhesive material and the lower flap having portions adapted to be sealed over the upper flap, said portions being provided with a seal sensitive to moisture or heat, all substantially as described.

4. As an improved article of manufacture, an envelope provided about its edge with a solid gum seal and an embossed line or lines along such seal, the end flaps having a portion of their upper surface cut away, the top flap having its under surface covered with an adhesive material and adapted to be sealed over a portion of the lower flap, and the lower flap having one or more portions adapted to be sealed over the upper flap, said portions being provided with a seal sensitive to moisture or heat, all substantially as described.

MARO S. CHAPMAN.
